UNITED STATES PATENT OFFICE.

JOHN C. BOERTLEIN, OF CLEVELAND, OHIO, ASSIGNOR TO THE GRASSELLI CHEMICAL COMPANY, OF CLEVELAND, OHIO, A CORPORATION OF OHIO.

APPARATUS FOR ANALYZING BY HEAT OF REACTION.

Application filed March 1, 1924. Serial No. 696,301.

In an article published in the Journal of the Society of Chemical Industry, volume 29, 1910, page 3 and following, there is described a method for the quantitative analysis of chemical products, such as sulfuric acid or oleum, by causing the same to react with some other material or reagent, such as water or dilute sulfuric acid, measuring the resulting heat of reaction and determining therefrom the composition of the chemical product.

An apparatus capable of carrying out analyses of this type is disclosed in an application in the name of Henry Howard, filed March 1, 1924, Ser. No. 696,274. Said apparatus comprises reservoirs for the chemical product and the reagent with overflows for maintaining constant levels therein, dippers mounted to rotate and dip into the reservoirs and deliver measured quantities of the two liquids into receptacles in which the average temperature of the two liquids is measured, and means for mixing the two liquids and measuring the temperature of the mixture. The difference between the equalizing temperature of the two liquids and the temperature of the mixture is a measure of the heat of reaction, as is apparent from the publication referred to and as is explained in the application referred to, by the use of resistance thermometers and a galvanometer and a suitably calibrated scale may be made to indicate the composition of the chemical product directly.

The present invention relates to a modified form of apparatus capable of performing the same functions.

In the drawing the single figure is a vertical elevational view with parts in section of the apparatus. Referring to the drawing, 1 is a basin having a suitable base or legs and provided on its upper edge with a groove containing a cushion or gasket 2 upon which rests the tubular case 3. The plate 4 closes the upper end of the case, both the plate 4 and the case 3 being held in place upon the basin 1 by means of bolts 5. Within the case 3 and resting also upon the upper edge of the basin 1 is a stand or supporting structure 6. A Dewar flask 7 is supported in the basin 1 in any suitable manner, for instance in a nest not illustrated. The stand 6 supports two cylindrical receptacles 8 and 9 provided with surrounding channels 10 and 11 having spouts 12 and 13 for catching

liquid overflowing therefrom and delivering the same into the funnel 14 which in turn empties into the basin 1 from which liquid flows through the pipe 15 to waste.

In the bottoms of the receptacles 8 and 9 are orifices 16 and 17 surrounded by upwardly extending peripheral walls 18 and 19 and downwardly extending peripheral walls 20 and 21. The walls 16 and 17 provide sediment traps in the bottoms of the receptacles, while the walls 20 and 21 extend through openings in the stand 6 into the two branches 22 and 23 of a Y-shaped tube, the third branch 24 of which extends into the Dewar flask 7. A thermometer 25 is supported by the plate 4, extending therethrough into the Dewar flask 7. The plate 4 also supports the supply pipes 26 and 27 which deliver into the receptacles 8 and 9, respectively. At the upper ends of the supply pipes 26 and 27 are T-connections 28 and 29 into the lateral openings of which are connected the feed pipes 30 and 31 and in the upper openings of which are supported in any suitable manner, not illustrated, the thermometers 32 and 33 which extend downwardly through the supply pipes 26 and 27 into the receptacles 8 and 9.

The apparatus operates as follows, assuming for convenience that the chemical product to be analyzed is oleum and the reagent is sulfuric acid solution, hereafter called test acid, containing sufficient free water to hydrate the free SO_3 in the oleum.

Oleum and test acid enter the apparatus through the feed pipes 30 and 31, flowing through the T-connections 28 and 29 and the supply pipes 26 and 27 into the receptacles 8 and 9. The thermometers 32 and 33 measure the average temperature of the oleum and test acid in the receptacles 8 and 9. The oleum and test acid are supplied to the receptacles 8 and 9 at rates sufficient to maintain them full to overflowing, thus maintaining constant heads of the liquids on the orifices 16 and 17, as a result of which substantially constant amounts of the oleum and test acid are delivered through the orifices and branches 22 and 23 of the Y-shaped tube into the branch 24 in which the two liquids mix. The mixture flows through the branch 24 into the Dewar flask 7 in which the temperature of the mixture is measured by thermometer 25. The overflow from the Dewar flask as well as the

overflow from the receptacles 8 and 9 is collected in the basin 1 and flows to waste through the pipe 15. Any sediment in the oleum or test acid deposits in the sediment traps formed by the walls 16 and 17 in the bottoms of the receptacles 8 and 9, thus avoiding any disturbance of the flow through the orifices. The orifices of course should be carefully constructed in order to provide for a uniform steady flow and they may be of any suitable relative sizes, that is, of equal size or unequal size, since in either case a calibration of the instrument must be made before the temperature difference indicated by the two thermometers 32 and 33 and the thermometer 25 may be made to indicate the analysis of the oleum.

The apparatus may be made of any suitable materials, for instance, if oleum is to be tested, the basin 1 and cover plate 4 may be made of cast iron or steel and the remainder of the apparatus of glass. As is evident the apparatus is of simple and inexpensive construction and is free of moving parts.

I claim:

1. Apparatus for the continuous analysis of chemical products comprising a receptacle for a chemical product and a second receptacle for a reagent capable of reacting with said chemical product to produce a sensible heat change, means for measuring the equalizing temperature of the chemical

product and the reagent in said receptacles, means for continuously delivering constant flows of said chemical product and said reagent from said receptacles into a third receptacle, and means for measuring the temperature of the resulting mixture in said third receptacle.

2. Apparatus for the continuous analysis of chemical products comprising two receptacles provided with overflows, means for supplying said receptacles with a chemical product and a reagent respectively, orifices in said receptacles, means for delivering the chemical product and reagent flowing through said orifices into a third receptacle.

3. Apparatus for the continuous analysis of chemical products as defined in claim 2 in which a thermometer is positioned in each of said receptacles.

4. Apparatus for the continuous analysis of chemical products comprising two receptacles each provided with an overflow at the top and an orifice at the bottom, means for delivering a chemical product and a reagent into said two receptacles respectively, a Y-shaped tube positioned to receive chemical product and reagent delivered by said orifices and to deliver the same into a third receptacle, and means for measuring the temperatures in said receptacles.

In testimony whereof, I affix my signature.

JOHN C. BOERTLEIN.
